REFRIGERATING APPARATUS

Mason M. Roberts, Dayton, Ohio, assignor to
 Frigidaire Corporation, Dayton, Ohio, a corporation of Delaware

Application April 16, 1930, Serial No. 444,671

4 Claims. (Cl. 62—116)

This invention relates to refrigerating apparatus and particularly to the arrangement of a refrigerating element in a refrigerator cabinet.

One of the objects of this invention is to provide an improved arrangement of a refrigerating element in a refrigerator cabinet.

A further object of this invention is to arrange a refrigerating element within a refrigerator cabinet in such a manner so that the refrigerant control valves and operating mechanism thereof may be accessible from the exterior of said cabinet.

10 A further object is to arrange a refrigerating element within a refrigerator cabinet in such a manner so that the refrigerant valve and operating mechanism thereof are accessible from the exterior of said cabinet, and to arrange said cabinet in such a manner so that said valve and operating mechanism are accessible from the exterior of the room or apartment in which said cabinet is located.

Further objects and advantages of the present invention will be apparent from the following description, reference being had to the accompanying drawings, wherein a preferred form of 25 the present invention is clearly shown.

In the drawings:

Fig. 1 is a vertical cross sectional view of a refrigerator cabinet showing the refrigerating element and showing features embodying the present invention;

Fig. 2 is a view of a portion of the apparatus shown in Fig. 1 taken in the direction of the arrow 2—2 of Fig. 1;

35 Fig. 3 is a view similar to Fig. 2 and showing the closure means for the opening provided in the rear of the cabinet in an open position;

Fig. 4 is a view in cross section of a portion of the refrigerating element forming a part of the 40 present invention; and

Fig. 5 is a front view in elevation of the apparatus shown in Fig. 4.

Referring to the drawings the numeral 20 designates a refrigerator cabinet provided with a 45 cooling compartment 21 formed by an inner lining 23. The cabinet also includes suitable insulation 25 disposed between the inner lining 23 and an outer covering 27. A refrigerating element 30 is disposed within the cooling compartment 21. Any suitable refrigerant circulating element may be used for supplying refrigerant to the refrigerating element 30 and for instance a refrigerant circulating element of the type disclosed in the patent to Harry B. Hull No. 1,648,-

178 issued November 8, 1927. The cabinet also includes the usual opening 38 closed by door 40.

Referring more in detail to the drawings, the refrigerating element 30 may be suspended within the cooling compartment 21 in any suitable 60 manner, and for instance, may be clamped to the inner lining 23 along the rear wall thereof by screws 45 and may be supported at the opposite end of said refrigerating element by means 46. The refrigerating element illustrated includes a 65 container 48 adapted to contain a quantity of liquid refrigerant and includes means in the form of ducts 50 forming a freezing compartment adapted to receive a plurality of ice making receptacles 53. The container 48 is provided with 70 an end ring 55 which is clamped to the inner lining 23 by an outer ring 57 and the screws 45. Thus the end ring 55 will engage the inner lining 23 on the inner side thereof while the ring 57 will engage the lining 23 of the opposite side 75 thereof while the screws 45 will clamp the ring 55 and 57 to said lining to thus support the valve plate end of the refrigerating element to the inner lining 23.

The refrigerating element 30 is provided with 80 the usual valve plate 60 which is rigidly clamped to the end ring 55 by means of bolts 63. The valve plate 60 is adapted to support the usual float valve mechanism 65 within said container which is removable from said refrigerating element by the removal of the valve plate 60 which 85 may be accomplished by removal of the bolts 63. The valve plate is provided with refrigerant valve connections 70 and 71 on the outer side thereof. The connections 70 provides a connection for a vapor conduit 74 and the connection 71 provides a connection for liquid refrigerant conduit 75. The refrigerant valve connections 70 and 71 are provided with shut off valves not shown herein but clearly shown and 90 described in the copending application of Otto M. Summers, Serial No. 266,397 filed March 31, 1928.

The refrigerant conduits 74 and 75 may be received by an opening 80 provided in a wall 82 100 formed by the room or apartment in which the refrigerator cabinet 20 is located, the conduits leading to the refrigerant circulating element.

According to this invention the refrigerating element 30 is disposed on one side of the lining 105 23 while the valve plate 60 is accessible from the opposite side thereof. Thus the valve plate 60 extends through an opening 90 formed by the inner lining 23 and terminates between the lining 23 and the outer covering 27. The outer 110

covering 27 is provided with an opening 93 adjacent the valve plate 60, which opening is provided with swinging closure means 94. Suitable insulation 95 such as kapok may be inserted 5 around the valve plate 60 and refrigerant valves 70 and 71.

From the foregoing description it will be noted that there is provided a refrigerating element disposed within a refrigerator cabinet in such 10 a manner that the refrigerant valves and operating mechanism therefor are accessible from the exterior of said cabinet and also accessible from the exterior of the room or apartment in which said cabinet is located, which exterior of the 15 room or apartment may be the exterior of the building, or a hallway. In other words, complete repair of the refrigerating element may be accomplished without entering the apartment in which the refrigerator cabinet is located. In 20 order to do this all that is necessary is to pump the refrigerant from the container 48 then remove the conduits from the valve connections. After the conduits are removed, the valve plate 60 together with the float valve mechanism may 25 be removed, by removing the screws 63, the plate and float then may be withdrawn from the cabinet 20 through opening 93 provided in the rear of the cabinet and through opening 80 provided in the wall 82 which opening 80 may be normally closed by door 99. Also this arrangement 30 is advantageous should there be a leak between the valve plate 60 and ring 55 in which case the gas formed by the liquid refrigerant in the container 48 would not escape into the cooling compartment 21 which would be undesirable. Since 35 the refrigerant circulating element is disposed in the basement or any other room or apartment from the room or apartment in which the cabinet 20 is located, repairs of the refrigerant circulating element may be made without entering the apartment in which the cabinet 20 is 40 located.

While the form of embodiment of the invention as herein disclosed, constitutes a preferred 45 form, it is to be understood that other forms might be adopted, all coming within the scope of the claims which follow.

What is claimed is as follows:

1. Refrigerating apparatus comprising in 50 combination a cabinet having a wall, a refrigerating element for said cabinet, said refrigerating element including a container adapted to contain a quantity of liquid refrigerant and a valve carried by said container, said valve being adapted to receive a refrigerant conduit, said refrigerating element being disposed on one side 55 of said cabinet wall with said valve being accessible on the other side of said cabinet wall, a wall adjacent said valve being adapted to re-

ceive said conduit, said valve being accessible through an opening formed by said second named wall, and closure means for said second named wall adjacent said valve and on the opposite side of said cabinet.

2. Refrigerating apparatus comprising in combination a cabinet having an inner lining and an outer covering, a refrigerating element including a container adapted to contain a quantity of liquid refrigerant, means connected therewith forming a freezing compartment adapted to receive at least one ice making receptacle and a valve plate having a plurality of valve connections thereon, said plate being carried by said container, said valve connections being adapted to receive refrigerant conduits, said refrigerating element being disposed on one side of said inner lining with said valve plate and valve connections extending through said lining and terminating between the inner lining and said outer covering, an opening in said outer covering adjacent said valve plate and valve connections, insulation around said valve plate and valve connections, closure means for said opening in the outer covering, a wall adjacent said opening provided in the outer covering in said cabinet and adapted to receive said refrigerant conduits through an opening provided in said second named wall, and closure means for said opening provided in said second named wall.

3. Refrigerating apparatus comprising in combination, a cabinet having a wall, a refrigerating element for said cabinet, said refrigerating element including a valve adapted to receive a refrigerant conduit, said refrigerating element being disposed on one side of said cabinet wall with said valve being accessible from the other side of said cabinet wall, and a wall adjacent said valve being adapted to receive said conduit, said valve being accessible through an opening provided in said second named wall.

4. Refrigerating apparatus including an insulated cabinet having a food compartment therein, said food compartment having an insulated door forming one wall thereof, a cooling unit supported within said food compartment, said cooling unit having a freezing compartment therein containing freezing receptacles, said freezing compartment having an opening on the front of the cooling unit facing the insulated door for ready access to the freezing receptacles, said cooling unit having removable controlling means on the rear of the cooling unit, said food compartment having a removable wall portion at the rear of said cooling unit to provide ready access to the rear of the cooling unit and the removable controlling means.
